DESIGN FOR A PROJECTOR

Walter D. Teague, New York, and D'Arcy A. Young, Jr., Rochester, N. Y., assignors to Eastman Kodak Company, Rochester, N. Y., a corporation of New Jersey

Application July 9, 1937, Serial No. 70,326

Term of patent 14 years

To all whom it may concern:

Be it known that we, Walter D. Teague and D'Arcy A. Young, Jr., citizens of the United States of America residing in New York city, in the county of New York and State of New York, and residing in Rochester, in the county of Monroe and State of New York, respectively, have invented a new, original, and ornamental Design for Projectors, of which the following is a specification, reference being had to the accompanying drawing, forming a part thereof, in which

The figure is a perspective view of our projector showing portions of the front, side and top walls of our new design, the opposite side of which is substantially the same in appearance as the side shown.

We claim:

The ornamental design for a projector as shown and described.

WALTER D. TEAGUE.
